(57) **CLAIM**

We claim the ornamental design for a calibrator device, as shown and described.

DESCRIPTION

FIG. 1 is a front view of a calibrator device of our design; FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top rear perspective view thereof; and,

FIG. 8 is a top front perspective view thereof.

All broken lines represent portions of the calibrator device that form no part of the claimed subject matter.
